CLIFTON W. SHERMAN, OF BUFFALO, NEW YORK, ASSIGNOR TO THE NATIONAL MALLEABLE CASTINGS COMPANY, OF CLEVELAND, OHIO, A CORPORATION OF OHIO.

DRAFT-RIGGING FOR RAILWAY-CARS.

1,169,435.

Specification of Letters Patent. Patented Jan. 25, 1916.

Application filed February 8, 1911. Serial No. 606,917.

To all whom it may concern:

Be it known that I, CLIFTON W. SHERMAN, a citizen of the United States, residing at Buffalo, in the county of Erie and State of New York, have invented new and useful Improvements in Draft-Rigging for Railway-Cars, of which the following is a specification.

This invention relates to a cushioning device for railway draft-riggings and buffers in which the yielding resistance of the springs is supplemented by frictional engagement of the shoes with relatively stationary surfaces, the same being generally known as friction draft gears, and more particularly to a friction gear in which the frictional elements are comprised of a plurality of friction shoes arranged in successive sets and adapted to be forced against a friction member by wedging means. In all devices of this kind the buffering or cushioning capacity depends on the compression of the springs and the angle of the co-operating inclines of the shoes and wedges.

The object of the invention is to increase the frictional resistance within the limits now available for this mechanism and still permit of a proper release of the wedges and shoes when the pressure is removed.

In the accompanying drawings: Figure 1 is a fragmentary horizontal longitudinal section of the draft rigging of a railway car embodying one form of my invention. Fig. 2 is a vertical longitudinal section of the same in line 2-2, Fig. 1. Fig. 3 is a vertical transverse section in line 3-3, Fig. 1.

Similar letters of reference indicate corresponding parts throughout the several views.

Referring to Figs. 1-3, 1, 1, represent the draft sills or beams of the car which are arranged lengthwise and parallel underneath the body of the car, 2 and 3 the front and rear followers which are guided between said sills so as to be capable of moving horizontally forward and backward, 4 the pair of front stops or blocks secured to the inner sides of the sills and operating to limit the forward movement of the front follower, 5 the pair of rear stops or blocks secured to the inner sides of the sills and operating to limit the rearward movement of the rear follower, 6 the draw bar or

coupler shank arranged lengthwise in front of the front follower, and 7 the strap or yoke connected with the draw bar and loosely or slidably embracing the front and rear followers. These parts may be of any suitable and usual construction.

That part of the draft rigging or gearing which embodies my invention is constructed as follows:—The friction member 8, which I have shown in the form of a cylindrical casing, is arranged horizontally and lengthwise between the sills and supported between the longitudinal parts of the strap or yoke. The rear end of this friction member engages with the front side of the rear follower and is provided with a forwardly facing shoulder 9 while the front end of the same is separated from the rear side of the front follower by an intervening space or clearance. This friction member forms the friction or brake member and is incapable of lateral movement. Engaging the rear shoulder 9 of the friction member 8, there is a spring cushion which preferably consists of two coil springs 10, 11 of different diameters, the smaller one 10 being arranged axially within the larger one 11.

At the forward end of the friction member 8, and adjacent to the spring cushion, are arranged wedging friction members which cooperate with the spring cushion and the cylinder for absorbing, cushioning or relieving the impact against the car. These wedging friction members comprise a plurality of sets of such members each set constituting a complete friction device. Although the number of sets of wedging friction members may be varied, two sets of such members, an outer or front set, and an inner or rear set, as shown in the drawings, are preferred.

The front set of wedging friction members preferably comprises a plurality of friction or brake shoes 12, preferably three in number, arranged in an annular row and each having a friction face 13 and an inclined or wedging face 14, and a wedge member 15 arranged against the annular row of shoes and provided with a plurality of inclined faces 16 each of which engages with the inclined face of one of the companion shoes. The large ends of the shoes are preferably provided with flat transverse faces 17 and the large end of the wedge

member is provided with a flat transverse face 18.

The rear set of wedging frictional members is constructed substantially like the front set and comprises a plurality of friction or brake shoes 120, preferably three in number, arranged in an annular row and each having a friction face 130 and an inclined or wedging face 140, and a wedge member 150 arranged against the inner annular row of shoes and provided with a plurality of inclined faces 160 each of which engages with the inclined face 140 of one of the companion shoes. The large ends of the shoes of the inner or rear set are preferably provided with flat transverse faces 170 and the large end of the rear wedge member is provided with a flat transverse face 180.

As shown in Fig. 1, the two sets of wedging friction members are arranged tandem fashion and the flat faces at the large ends of the rear set of shoes bear against the front ends of the spiral springs of the cushion device and the flat faces on the large ends of the front set of shoes engage with the flat face of the large end of the rear wedge while the flat face on the large end of the front wedge bears against the rear side of the front follower.

The friction member 8 and the two annularly arranged sets of friction members are movably connected so as to be capable of axial movement relatively to each other, preferably by means of a longitudinal tie rod or bolt 20 arranged centrally within the springs, friction member and wedges and provided at its opposite ends with shoulders 21, 22 formed by the head and nut thereof which engage one with the outer side of the rear end of the friction member and the other with the outer side of the front wedge of the wedging friction members.

In the assembled condition of the parts, the springs and inner set of wedging friction members are arranged wholly in engagement with the friction member while the outer set of wedging friction members is arranged only part way in engagement with the friction member and projects forwardly therefrom. When the draw bar or coupler shank is moved backwardly by the impact with another draw bar or coupler the rear follower remains at rest and forms the abutment which receives the thrust while the front follower moves rearwardly. During this movement the wedges by reason of the engagement of their inclined faces with the corresponding faces of the companion shoes cause the latter to be wedged and their friction faces to bear with increased frictional pressure against the friction face of the friction member 8. While the shoes of both sets of wedging friction members are thus wedged into frictional engagement with the friction member 8 the frictional resistance

to the backward movement of the draw bar thus produced is added to the resistance of the springs.

The degree of resistance which is produced by the springs determines the degree of frictional engagement of the rear set of shoes with the friction member and the combined resistance produced by the springs and the frictional contact of the rear shoes with the friction member determines the degree of frictional engagement of the front shoes with the friction member. It follows from this that if the inclines of the front and rear sets of shoes were the same that the front shoes would be forced with a greater pressure against the friction member and consequently would do more work than the rear set of shoes so far as frictionally resisting the impact on the draft rigging.

In order to equalize or nearly so the work of both sets of shoes and obtain the maximum resisting effect within a given length of space the angles of the coöperating inclines of the two sets of shoes and wedges is so determined that the inner wedge will exert a greater thrust on the rear shoes than that exerted by the front wedge on the front shoes and thus compensate for the difference between the resistance to the longitudinal movement encountered by the two sets of shoes and wedges.

The relative angle of the coöperating inclined surfaces of the two sets of shoes and wedges may be of any degree which may be found suitable or desirable in practice for a particular weight of car for properly resisting the impact at any part of the stroke and still permit of proper release or return movement to normal position of the wedges and shoes as the impact on the same relaxes. Although the angles of the inclines on the shoes and wedges for this purpose may vary those which are represented in the drawings, for example, are suitable. As shown in the drawings, the coöperating inclines of the rear shoes and wedges are at an angle of thirty-five degrees and the angle of the coöperating inclines of the front set of shoes and wedges is forty-five degrees. Owing to this difference in the angles of the inclines of the two sets of shoes and wedges the forward or inward movement of the draw bar causes both sets of shoes to bear with equal or nearly equal pressure against the friction member 8.

It will thus be apparent that the frictional capacity of this device is dependent directly upon the resistance behind each set of shoes and wedge, and that springs constitute the sole means of resisting the inward movement of the rear shoes and wedge and therefore control the wedging of the rear shoes; while the combined tension of the springs and the frictional capacity of the rear shoes and wedge resists the forward or inward

movement of the front set of shoes and wedges and controls the wedging action of the front shoes, thereby intensifying the spring action and frictional resistance and 5 multiplying the capacity of the draft rigging accordingly. The aggregate frictional resistance which it is possible to obtain by this means is much greater than when the two sets of shoes and wedges have inclines 10 of the same angle, and very much greater than it has been possible to obtain heretofore by other means within the space now available on cars of standard construction. When the draw bar is pulled forward the 15 front follower becomes the abutment in which case the friction member 8 and springs are moved toward the two sets of wedging friction members and the wedging pressure upon the shoes by the wedges is 20 effected. When the impact on the cushioning device has spent itself the followers are separated one from the other by the expansion of the springs and at this time the wedges release themselves from the shoes 25 and the latter release their grip on the friction member 8.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within 35 the scope of the invention claimed.

I claim as my invention:

1. In a draft gear, a shell having an internal cylindrical friction face, a plurality of sets of segmental friction blocks arranged 40 end to end within the shell, a wedge within each set of friction blocks, each set of friction blocks having external faces frictionally engaging the shell, internal forward angular friction faces engaging the wedge and flat 45 rear faces, each wedge comprising a single non-collapsible member and the co-operating inclined faces of one set of friction blocks and wedge being of a different angle from the angle of the co-operating inclined faces 50 of the blocks and wedge of the other set.

2. A draft rigging for railway cars comprising a cylinder forming an outer friction member, a plurality of sets of inner friction members, said sets being arranged tandem in one end of said cylinder and each set comprising a plurality of shoes arranged in an annular row and each shoe having a curved outer face which engages the bore of the cylinder, a flat rear face arranged at 55 right angles to the axis of said cylinder and an inclined front face, and a wedge or spreader having inclined rear faces engaging with the inclined front faces of the companion shoes and a flat front face arranged 60 at right angles to the axis of the cylinder,

and a spring arranged in the opposite end of the cylinder and operating to resist longitudinal movement of said inner and outer friction members relatively to each other, the rear faces of the shoes of the rear set 70 bearing against the front end of the spring and the rear faces of the shoes of the front set engaging with the front face of the wedge of the rear set and the co-operating inclined faces of the front shoes and wedge 75 being of a greater angle than the angle of the co-operating inclines of the rear shoes and wedge.

3. In frictional shock absorbing mechanism, a member having a friction surface, a plurality of sets of friction shoes in frictional engagement therewith, a plurality of wedge members in wedging engagement with said shoes, said wedges and sets of shoes being arranged alternately and in tandem, and 80 a spring, the angle of wedging engagement between the wedge and set of shoes nearest said spring being more acute than the angle of wedging engagement between the wedge and set of shoes farthest from said spring, 90 whereby the amount of frictional work absorbed by the nearer set is relatively increased, and the amount of work absorbed by the remoter set is relatively diminished.

4. In frictional shock absorbing mechanism, a member having a friction surface, a plurality of sets of friction shoes in frictional engagement therewith, a plurality of wedge members in wedging engagement with said shoes, said wedges and sets of shoes being arranged alternately and in tandem, and 95 a spring, the acuteness of the wedging angle between successive sets of contacting wedges and shoes being progressively increased toward the spring, whereby the amount of 100 frictional work absorbed by the sets of segments is substantially equalized.

5. In frictional shock absorbing mechanism, a member having a frictional surface, a plurality of sets of friction shoes in frictional engagement therewith, a plurality of wedge members in wedging engagement with said shoes, said wedges and sets of shoes being arranged alternately and in tandem, and a spring, the angle of wedging engagement 110 between the wedge and set of shoes nearest the spring being more acute than the angle of wedging engagement between the wedge and set of shoes farthest from the spring, and the frictional bearing surface of the set 115 of segments nearest the spring being less in area than the frictional bearing surface of the set farthest from the spring, whereby the amount of frictional work performed by the nearer set of segments is increased, and the intensity of pressure on their friction surfaces is increased, and the amount of frictional work and the intensity of pressure on the set of segments more remote from the 120 spring are decreased.

6. In frictional shock absorbing mechanism, a member having a frictional surface, a plurality of sets of friction shoes in frictional engagement therewith, a plurality of wedge members in wedging engagement with said shoes, said wedges and sets of shoes being arranged alternately and in tandem, and a spring, the acuteness of the wedging angle between successive sets of contacting wedges and shoes being progressively increased toward the spring, and the frictional bearing surfaces of successive sets of shoes being progressively increased in area away from the spring, whereby the amount of frictional work performed, and the intensity of pressure on the friction surface is substantially equalized.
7. In frictional shock absorbing mechanism, a member having a friction surface, a plurality of sets of friction shoes in frictional engagement therewith, a plurality of wedge members in wedging engagement with said shoes, said wedges and sets of shoes being arranged alternately and in tandem, and a spring, the frictional bearing surfaces of the successive sets of shoes being

progressively decreased in area toward the spring, whereby the intensity of pressure upon the frictional surfaces of the sets of segments is substantially equalized.

8. In friction draft or buffing mechanism, a casing having an internal frictional surface, a plurality of sets of friction shoes having their outer surfaces in engagement therewith and having inner wedge faces, a plurality of wedge members co-acting with the inner wedging faces of the friction shoes, said wedges and sets of shoes being arranged alternately and in tandem, and a spring, the frictional bearing surfaces of the successive sets of shoes being progressively decreased in area toward the spring, whereby the intensity of pressure upon the frictional surfaces of the sets of segments is substantially equalized.

Witness my hand this 3rd day of February, 1911.

CLIFTON W. SHERMAN.
